PADLOCK

Henry G. Voight, Hamden, Conn., assignor to
Sargent & Company, New Haven, Conn., a cor-
poration of Connecticut

Application August 14, 1942, Serial No. 454,778

4 Claims. (Cl. 70—38)

This invention relates to padlocks more particularly made up of a plurality of plates or laminated sections superposed one on the other to construct the body or case of the lock.

In the construction of a padlock from laminated or superposed plates or sections, some difficulty has heretofore been encountered in the assembling of the parts of the lock. Such a lock may, of course, be made very economically, as the elements from which the case is constructed may be fabricated by stamping operations from flat stock. While these parts may be readily assembled and secured together, there are certain movable elements which go to make up the lock which must either be put into place during the assembly of the plates, or, if possible, installed thereafter. One of these parts is the shackle which is mounted for reciprocation in the lock case, but which should be secured against complete detachment when it is in unlocked position. Usually it has been the custom in a lock of this kind to insert the shackle during the assembly of the lock body, and secure it in place by a pin or similar element which must be driven into place while the lock sections are held in assembled relation.

One object of the present invention is to provide a lock the parts of which may be easily assembled, and to provide for the insertion of the shackle into the lock case after the latter has been completely assembled.

A still further object of the invention is to provide a padlock having a case constructed of superposed plate-like sections forming the lock body, into which body the shackle may be inserted after the sections have been assembled, and to provide means for automatically securing the shackle against detachment from the body of the lock upon its insertion therein.

A still further object of the invention is to provide a padlock of the character described having a spring-pressed shackle-latching member mounted therein and adapted to be protracted into the shackle opening, whereby the shackle may be inserted in this opening and thereafter retained by the latching member against complete detachment from the body of the lock.

To these and other ends the invention consists in the novel features and combinations of parts to be hereinafter described and claimed.

In the accompanying drawing:

Fig. 1 is a side elevational view of a padlock embodying my invention;

Fig. 2 is a top plan view of the same;

Fig. 3 is a bottom plan view of the lock;

Fig. 4 is a sectional view on line 4—4 of Fig. 2; Figs. 5 and 6 are, respectively, sectional views on lines 5—5 and 6—6 of Fig. 4;

Figs. 7, 8 and 9 are detail plan views of certain of the laminated sections from which the lock is made;

Fig. 10 is a side elevational view of the locking bolt; and

Fig. 11 is a bottom plan view of the bolt shown in Fig. 10.

To illustrate a preferred embodiment of my invention, I have shown a lock comprising a body 10 made up of a plurality of laminated sections which will be described in detail hereinafter.

15 These sections are, as will be explained, of various conformations with respect to the openings therein to receive the working parts of the lock. It will be understood that the plates are all of the same outline, however, so that when superposed and firmly secured together under pressure, if desired, the outer surface of the lock will have a smooth outline.

In the present instance the bolt of the lock is designed to be operated by a pin tumbler locking mechanism, and the plates are arranged to receive a structure of this kind. It will be understood, however, that the lock is not limited to a locking mechanism of this character. This mechanism comprises the usual key barrel 11 rotatably mounted within a case 12 having a pin tumbler extension 13 and a projecting pin 14 mounted eccentrically on the upper end of the key barrel. These parts may be of the usual form found in pin tumbler locks.

35 The shackle 15 of the lock is of the usual U-shaped form adapted to be inserted in openings in the case, the shackle being provided with recesses 16 to receive the ends of an oscillatable bolt 17 in order to lock the shackle within the case.

40 One leg of the shackle is longer than the other, as shown at 18, and is urged upwardly by a spring 19 seated in the lower end of the shackle opening in the case. This leg of the shackle is provided with a recess or cut-away portion 20 in one side 45 thereof, and with an annular recess 21 and a lower head 22 below this recess, the lower portion of which is beveled, as shown at 23.

The body of the lock, as stated, is made up of a plurality of laminated plates, which will now be described. The lower of these plates, *a*, is provided with a single centrally disposed opening to receive the outer end of the key barrel 11, as shown in Figs. 3 and 4. Above this are a group of plates identical in form designated by the reference character *b*, and shown in Fig. 9 of the

drawing. These plates have openings 24 therein of keyhole shape to snugly receive the pin tumbler lock casing 12 and extension 13 so as to hold the latter securely in place. They will also be provided with openings 25 to receive the longer leg of the shackle 15. Above the plates *b* is a plate *c* having an opening 26 of substantially the same shape as the openings 24 to receive the key barrel, which opening may be provided with recesses 27 at each side, and the plate *c* is also provided with an upwardly projecting pin 28.

Above the plate *c* is a plate *d*, shown in Fig. 6 of the drawing. Beside being provided with shackle openings 25, this plate is provided with an opening 29 of irregular shape, which opening communicates with one of the shackle openings 25. The pin 14 on the upper end of the key barrel extends into the opening 29, and also pivotally mounted in the opening 29 is a shackle-latching member 30 pivoted upon the pin 28, previously described. Reacting against the sides of the opening 29 is a spring 31, one leg of which presses against the latch 30 to urge it toward the leg of the shackle. As will be seen from Fig. 4, this latching member will be projected by the spring 31 into the cut-away portion 20 of the shackle, so that, while it permits longitudinal movement of this leg of the shackle as limited by the length of this recess or cut-away portion thereof, it will, when the shackle is projected upwardly by the spring 19, engage the head 22 and prevent the complete detachment of the shackle from the case.

The upper face of the latch member 30 is beveled adjacent the edge thereof which lies against the shackle, as shown at 32, whereby when during the assembly of the parts the leg of the shackle is inserted into the opening in the case, the beveled lower portion 23 of the shackle head 22 will strike the beveled portion 32 of the latch member and cam it rearwardly against the action of the spring 31 to permit the shackle to enter its opening. After the head 22 has passed below the latching member 30, the latter will be immediately projected by its spring into the recess or cut-away portion 20.

Above the plate *d* are a pair of plates *e* of the form shown in Fig. 7, these plates being provided with shackle openings 25 and with a central opening 34 to receive the hub 35 of the locking bolt and mount the latter for rotatable movement, as will be more fully described hereinafter. Above the plates *e* are a pair of plates *f*, shown in Fig. 5, these plates having openings 36 of irregular shape to receive for oscillating movement the lock bolt 17.

This lock bolt, as shown more particularly in Figs. 5, 10 and 11, may itself be made up of laminated plates, although the method of its manufacture may be varied if desired. It is provided with a central hub portion 35, and projecting wing or bolt portions 37 designed to extend outwardly from the hub portion and engage within the notches or recesses 16 of the shackle 15. A spring 38 mounted in the openings 36 of the plates *f* normally urges the bolt into locking position, as shown in Fig. 5. The hub 35 of the bolt is provided with a notch or recess 39 within which stands the pin 14, so that when the key barrel is rotated or oscillated the bolt will be caused to oscillate and will be moved into the enlarged corners of the opening 36 out of engagement with the legs of the shackle.

The case of the lock is then completed by the two upper plates *g* (Fig. 2), which are merely

provided with openings 25 to receive the legs of the shackle. The parts of the case may be secured together by rivets 40 adjacent the four corners thereof, each of the plates being provided with openings 41 to receive such rivets.

In the assembly of the parts, the lock case 12 is placed upon the lower plate *a*, with the lower portion of the key barrel 11 received in the opening in this plate. The upper plates are 10 then placed thereon until the plate *d* is reached, at which time the latch member 30 is placed in the opening 29 on the pin 28, and the spring 31 is also placed in position, as shown in Fig. 6. At this time the spring 19 may be dropped into the 15 lower end of the shackle opening. The plates *e* and *f* are next superposed upon the plate *d*, and the bolt 17 placed in position in the opening 36, as is also the spring 38. The case is then completed by the two upper plates *g*, and the plates 20 are then riveted together under pressure, if desired, so as to provide a lock case having the same cross-sectional conformation as the outline of the plates themselves, and having a smooth exterior surface.

25 After the lock body has been completely assembled, as explained above, the shackle may be inserted into the shackle openings 25. The bolt 17 may be rotated to inoperative position by the key, not shown, so that the shackle opening 30 will be unobstructed until the beveled edge 23 of the head 22 on the longer leg of the shackle strikes the beveled edge 32 of the shackle latch member 30. The latch member will be cammed inwardly, thus permitting the head 22 of the 35 shackle to pass below the latch 30, at which time the latter will move outwardly under influence of the spring 31 into the notch or cutaway portion 20 on the longer leg of the shackle. The lock is now completely assembled, and if it is desired to lock the shackle is rotated until the shorter end stands above the shackle opening 25 adapted to receive it, at which time the shackle is pressed inwardly against the action of the spring 19 in the usual manner. 40 When the shackle reaches the position at which the notches 16 lie opposite the wings 37 of the bolt 17, the latter will be urged by the spring 38 into these notches, as shown in full lines in Fig. 5, thus locking both legs of the shackle in place.

45 When the key barrel is rotated in a direction to unlock the shackle, the pin 14 engaging the edge of the notch 39 in hub 35 of the bolt 17 will oscillate the bolt, and thus swing the wings 37 to a position to release the shackle, allowing the latter to be propelled upwardly by the spring 19 until the upper surface of the head 22 strikes against the latch member 30, thus arresting the outward movement of the shackle. In this position the latch member 30 lies within the annular recess 21, so that the shackle may be rotated about its longer leg. It may be noted from inspection of Figs. 5 and 6 that the flat side of the recess 20 is at a slight angle with respect to the flat side of the recess 16 on the longer leg of the shackle, so that when the shackle is open and is turned to a position in which it may be closed, where the shorter leg lies opposite its opening 25, the engaging ends of the bolt 17, which at that time engage the longer leg of the shackle, will be held in an inoperative position by the rounded portion of the shackle leg, thus permitting easy insertion of the short end of the shackle into its opening 25.

50 While I have shown and described a preferred embodiment of my invention, it will be under-

stood that it is not to be limited to all of the details shown, but is capable of modification and variation within the spirit of the invention and the scope of the claims.

What I claim is:

1. A padlock comprising a case comprising a plurality of superposed plates, a shackle cooperating with the case and having one leg longer than the other, a locking element engaging the shackle to hold it in locked position, and means to prevent detachment of the shackle from the case when the former is unlocked, said means comprising a member pivoted on one of said plates to swing parallel with the surface thereof below the locking member, and a shoulder on the longer leg of the shackle with which said member engages.

2. A padlock having a case comprising a plurality of laminated plates superposed one on the other and secured together, said plates being provided with registering shackle-receiving openings, a locking bolt movably mounted in the case, a shackle insertable into said openings after assembly of the plates, and latching means carried by one of said plates and disposed in an opening in an adjacent plate and automatically moved into engagement with the shackle after insertion thereof to prevent detachment of the shackle from the case when the shackle is in unlocked position.

3. A padlock having a case comprising a plurality of laminated plates superposed one on the

other and secured together, said plates being provided with registering shackle-receiving openings, a locking bolt movably mounted in the case, a shackle insertable into said openings after assembly of the plates, one of said plates having an opening communicating with the shackle opening, and means within said opening automatically moved into engagement with the shackle after insertion thereof to prevent

5 detachment of the shackle from the case when the shackle is in unlocked position, said means comprising a latch member pivoted to an adjacent plate and spring pressed toward the shackle.

10 4. A padlock having a case comprising a plurality of laminated plates superposed one on the other and secured together, said plates being provided with registering shackle-receiving openings, a locking bolt movably mounted in the case, a shackle insertable into said openings

15 after assembly of the plates, and means automatically moved into engagement with the shackle after insertion thereof to prevent detachment of the shackle from the case when the shackle is in unlocked position, said means comprising a latch member pivoted to one plate and lying within an opening in an adjacent plate and spring pressed toward the shackle, and said

20 latch member and shackle having co-acting portions effective to cam said member out of the path of the shackle during the insertion of the latter.

HENRY G. VOIGHT.
